UNITED STATES PATENT OFFICE.

ELMER HARRISON, OF PHILADELPHIA, PENNSYLVANIA.

RACK FOR GRAIN-SHOCKS AND THE LIKE.

No. 868,433.

Specification of Letters Patent.

Patented Oct. 15, 1907.

Application filed July 12, 1907. Serial No. 383,403.

To all whom it may concern:

Be it known that I, ELMER HARRISON, a citizen of the United States, residing at Philadelphia, county of Philadelphia, and State of Pennsylvania, have invented 5 a certain new and useful Improvement in Racks for Grain-Shocks and the Like, of which the following is a specification.

My invention relates to a new and useful improvement in racks for grain shocks and the like, and has for 10 its object to provide an exceedingly simple and effective device of this description which when not in use may be folded into small space for storing or shipping, and which may be readily opened so that the grain may be stacked thereon to make a shock, after which the top 15 may be brought into position to protect the grain from rain.

A further object of my invention is to prevent the shock coming in contact with the ground, and at the same time provide free ventilation therefor so as to 20 avoid the rotting of the straw or molding of the grain.

With these ends in view, this invention consists in the details of construction and combination of elements hereinafter set forth and then specifically designated by the claims.

25 In order that those skilled in the art to which this invention appertains may understand how to make and use the same, I will describe its construction in detail, referring by letter to the accompanying drawing forming a part of this specification, in which—

30 Figure 1 is a perspective of my improvement when adjusted for use. Fig. 2, a similar view showing one-half of the top folded, the other half being swung back.

In carrying out my invention as here embodied, A represents the base, which is composed of two strips on 35 each side connected together by a strip at each end, and having the cross rails B and C.

D and D' are arms, the former being pivoted to the end pieces of the base, while the latter are pivoted to the cross rails B so that they will pass each other in 40 folding.

To the upper ends of the arms D and D' are pivoted the arms E and E', and these arms E and E' have secured thereto the roof boards F and F', by which arrangement these roof boards may be swung in the position shown in Fig. 1 and there secured by the hooks G, 45 it being noted that the roof board F overlaps the roof board F' so as to facilitate the shedding of rain.

The upper portion of the base is covered with the

screen H, upon which the shock is set, thus holding the shock out of contact with the ground and at the same 50 time permitting free passage of air to the shock.

When the apparatus is not in use it may be folded, as partly shown in Fig. 2, and when both of the roof boards are folded upon the base they will be held in this position by the turn bolt I.

In practice when the apparatus is to be used, it is placed upon the ground in the position where it is intended to form a shock and the sheaves of wheat or other grain are stacked upon the screen, and when the shock is made and tied the roof boards are swung into 60 position and hooked so as to cover the grain and shield the water therefrom, and as air may gain free access to the shock it follows that neither the straw or the grain become musty or molded, and when the shock has been removed the apparatus may be folded, as before described and stored for further use, it being understood 65 that a number of these apparatuses are used in shocking grain, one being provided for each shock.

Of course I do not wish to be limited to the exact details of construction here shown as these may be varied within reasonable limits without departing from the spirit of my invention.

Having thus fully described my invention, what I claim as new and useful, is—

1. In a shocking rack the combination of a base, a 75 screen secured to said base, arms pivoted to the base, a second set of arms pivoted to the first named arms and roofing boards carried by the second set of arms, as and for the purpose set forth.

2. A grain shocking apparatus consisting of a base, 80 side rails secured to said base, a screen also secured to the base, a series of pivoted arms, roofing boards secured to said arms, means for holding said roofing boards in their open position and means for holding said boards in their folded position, as specified.

3. The herein described combination of a base, cross rails secured to said base, a screen also secured to the base, two series of arms D and D' pivoted to the base, cross rails, a second series of arms E and E' pivoted to the first named arms, roofing boards secured to the arms E and E', hooks for holding the roofing boards in their open position and a turn bolt for holding the movable parts in their folded position, as specified.

In testimony whereof, I have hereunto affixed my signature in the presence of two subscribing witnesses.

ELMER HARRISON.
